[57] CLAIM

The ornamental design for a frontpiece for swim goggles, as shown and described.

DESCRIPTION

FIG. 1 is an isometric view from the front, top and one side of a frontpiece for swim goggles showing our new design; FIG. 2 is a front elevational view thereof;

FIG. 3 is a top plan view thereof;

FIG. 4 is a back elevational view thereof;

FIG. 5 is a bottom plan view thereof; and.

FIG. 6 is a side elevational view thereof, the other side being a mirror image thereof.

The drawing is shaded for contrasting color.
